United States Patent Office.

FRANCIS A. PRATT, OF HARTFORD, CONNECTICUT.

Letters Patent No. 93,903, dated August 17, 1869.

IMPROVEMENT IN MACHINES FOR PLANING METAL.

The Schedule referred to in these Letters Patent and making part of the same.

To all whom it may concern:

Be it known that I, FRANCIS A. PRATT, of the city and county of Hartford, and State of Connecticut, have invented certain new and useful Improvements in Slipper-Device for Metal-Planers; and to enable others skilled in the art to make and use the same, I will proceed to describe its construction, referring to the drawings, in which the same letters indicate like parts in each of the figures.

The nature of this invention will be understood from the specification and drawings, the object of which is saving time in moving the slides or shipping-dogs upon a planer-table, whenever it becomes necessary to run the table back beyond the place where it may be working, as is the case when oiling or changing the work upon the table. It is often the case that this has to be done a great number of times during the day, and as often makes it necessary to unscrew the shipping-dog on the table, which each time makes a nice adjustment necessary.

Now, my improvement obviates this difficulty, and renders but one adjustment necessary during the whole time consumed in planing, when the planer is running on the same kind of work, or until the work is removed or changed.

In the accompanying drawings—

Figure 1 is an end view of a metal-planer, below the upper side of the sliding bed.

Figure 2 is a side view of the same.

k is the bed of the machine.

k' is the table, upon which the work is secured in the common way.

k'' are the supporting-legs.

m are driving-pulleys, arranged upon the end of a shaft, *m'*.

c are arms, or belt-guides, which change or guide the belt from one pulley to the other.

e are adjustable stops, secured to the edge of the table-bed *k'*, by means of set-screws or bolts.

a' is a grooved oscillating cam, arranged upon a shaft, *b*, all of which are constructed and actuated in the common way.

g is a sliding shipper-block, which is fitted and works back and forth upon the projecting edge of the bed *k*, also in the common way.

d is an oscillating or swinging dog, secured upon the block *g*, and turned over toward the bed *k'*, and between the stops *e*.

f is a stud-pin, secured in the lower portion of the box *g*, the lower end of which, or a friction-wheel thereon, works in the groove *a* of the cam *a'*, which is arranged and oscillates with the shaft *b*, the latter having a projecting arm, *b''*, which connects with the shaft *b'*, upon which the belt-shippers *c* are arranged.

Thus it will be seen that when motion is once given to the machine in the common way, and the dog *d* is turned in toward the bed *k*, and between the stops *e*, it will be acted upon thereby, and by their action the

stud-pin, or roller thereon, will work in the groove *a* of the cam *a'*, and produce a rolling or reciprocating motion of the shaft *b*, and thereby of the arm *b''* on said shaft *b*, which actuates or changes the guides *c* alternately from one pulley to the other.

I do not wish to confine myself to the use of the hinged swinging dog *d*, as the same result may be produced in various equivalent ways, as in Figure 4, by providing the adjustable stops *e* with a hinge-piece, *h*, which can be lifted to allow the stops to pass the shipper-box *g*.

In Figure 5 is another modification, to produce the same result, where a pin, *i*, is arranged to operate through the stops *e*, which alternately strike an elevation, *g'*, formed or secured on the shipper-box *g*.

In Figure 6 is shown how the same result may be produced by a horizontal-sliding pin, *h''*, which moves in a line, at right angle with the side of the bed, upon which the work is secured, the end of which interposes between the stops *e*.

All these, and many more or other equivalent ways, may be arranged to produce the same result. But I chose and believe that the swinging piece *d*, as shown, is the best adapted, and most convenient for use.

When the workman has his work upon the table, especially if it is short work, it comes so far under the cross-beam that it becomes necessary to loosen the stops *e*, so that the work may pass from under the frame, that he may be able to remove it and replace another.

By the use of this swinging piece *d*, he has only to swing, or remove this piece *d* from between the stops *e*, when the table is free to be moved to any desirable place upon its ways, without loosening or changing the stops *e*, thereby saving much vexatious trouble and loss of time; and after removing the piece of work from the table, and replacing another, he has only to run the table up, and swing or place the movable stop *d* between the stops *e*, which puts the whole apparatus back in the same place, without the necessity of resetting the shipping-dogs or stops *e*.

I believe I have thus shown the nature, construction, and adaptation of this improvement, so as to enable others skilled in the art to make and use the same therefrom.

What I claim, and desire to secure by Letters Patent, is—

The arrangement of the swinging dog *d* upon the sliding block *g*, in combination with the bed *k'*, stops *e*, pin *f*, cam *a'*, upon the shaft *b*, gear-connection *b'*, and guide-arms *c*, to connect and disconnect the shipper from the bed *k'*, substantially as set forth.

FRANCIS A. PRATT. [L. S.]
